INFANT'S PLAY YARD

Rubert C. Bockus, Gardner, and Henry J. Landry,
South Ashburnham, Mass., assignors to Gem
Crib and Cradle Company, Gardner, Mass., a
corporation of Massachusetts

Application July 13, 1943, Serial No. 494,488

6 Claims. (Cl. 5—99)

This invention relates to infants' play yards or pens and the like, and the principal objects of the invention include the provision of an article of manufacture of the class described which avoids the use of metal hardware but which still is foldable in the nature of the conventional play yard and is strong and sturdy; and the provision of a novel corner block having three functions and serving as a support, a pivot piece for the yard bottom or floor element, and as a pivot for the folding side frame walls.

Other objects and advantages of the invention will appear hereinafter.

Reference is to be had to the accompanying drawings in which

Fig. 1 is a side view of a play yard according to the invention and showing one-half of the bottom or floor raised;

Fig. 2 is a side view of one end of the play yard showing the attached bottom or floor element raised;

Fig. 3 is an enlarged view of the corner block;

Fig. 4 is a bottom plan view of the yard with a bottom or floor element raised;

Fig. 5 is a horizontal sectional view of the yard in folded condition and having parts broken away; and

Fig. 6 is a perspective view of the corner block.

The new play yard comprises a pair of opposite walls each having bottom rail 10, top rail 12, and connecting spindles 14. These walls are rigid and form the outer sides of the play yard when collapsed. Corner blocks 16, each having an outline as represented in Fig. 3, are secured to rails 10 at their ends, and these blocks not only provide the corner supports but also form pivot blocks for the bottom or floor elements 18 and for the folding side frames 20.

Each corner block 16 has a cut-out recess at 22 to receive the bottom rails 10, see Fig. 1, and an oppositely extending tongue 24 receiving the bifurcated ends 26 of the bottom rails of the folding side frames 20. Pins 30 pivot these parts together and for easier swinging they are rounded off, see Fig. 5.

Complementary top blocks 32 secured at the ends of rails 12 are provided with tongues 25 similar to tongues 24 and are received between the arms of a yoke at 27 formed by bifurcations in the ends of the top rails of the frames 20. Pins 29 pivot the tongues to the yoke. Frames 20 are pivoted together on pins 31 passing thru bifurcations at 33 receiving pivoted blocks 34.

Bottom or floor elements 18 comprise slats 36 secured to a plurality of bottom cross cleats

38. One cleat has blocks 40 thereon for ground support, and the other cleats stop short of the outside slat providing space for short longitudinal cleats 42. Cleats 42 are provided with end dowels 44 for reception in bores 46 in corner blocks 16 so that the floor elements 18 may be swung on horizontal axes from extended floor forming locations to folded vertical positions.

Stops 48 form rests for the floor elements and 10 if desired pins 50 may be used to enter bores in stops 48 in extended condition of the floor elements to prevent lateral play of the parts.

The parts are easily assembled so far as the sides and folding frames are concerned, but the 15 floor elements are best assembled by turning the yard on its side and inserting a dowel 44 in a corner block on the ground, arranging the floor elements in correct position, inserting a dowel 44 on a loose cleat 42 in the upper corner block, 20 and finally securing the loose cleat to the slats and cleats 38 adjoining.

The entire play yard may be made of wood, including the corner blocks 16, dowels 30 and 44, connections 34, supports 40, rests 48, and pins 25 50. Nails may be used if desired to aid in securing slats 36 to their cleats.

Particular attention is directed to the corner blocks 16 which act as ground supports and as 30 pivot blocks for the folding frames and the swinging floor elements.

Having thus described our invention and the 35 advantages thereof, we do not wish to be limited to the details herein disclosed, otherwise than as set forth in the claims, but what we claim is:

1. A device of the class described comprising a 40 pair of side walls, a pair of folding frames connecting the side walls in rectangularly spaced relation, a supporting corner block secured to each lower end of each side wall, a tongue and yoke pivot joint connection connecting each block to a folding frame, and pivot joints at the top of each folding frame pivotally securing the latter to a side wall, said blocks supporting the side walls and folding frames, the latter folding inwardly 45 toward each other.

2. A device as recited in claim 1 including 50 dowel pins forming the pivots for the tongue and yoke pivot joints.

3. A device of the class described comprising a 55 pair of rigid side walls, a pair of infolding frames connected to the side walls at the ends thereof, a supporting corner block fixedly secured to each lower end of each side wall, a pivot connection securing each corner block to its adjacent folding frame, and pivot joints at the tops of the side

walls swingably connecting the latter and the folding frames, all said pivot joints being on vertical axes, said blocks supporting the side walls and thereby the folding frames.

4. A device of the class described comprising a pair of rigid side walls, a supporting block secured to each lower end of each side wall, in-folding frames pivoted to the blocks, and a pair of floor elements, each of said floor elements being pivot-ed to a separate pair of supporting blocks.

5. A device of the class described comprising a pair of rigid side walls set up vertically in spaced

relation, a supporting block secured to each lower end of each side wall, in-folding frames pivoted to the supporting blocks on vertical pivots, and floor elements each swingably mounted on the supporting blocks secured to each individual side wall, said floor elements swinging about a horizontal axis through the blocks.

6. A device as recited in claim 4 including tongue and yoke pivot connections between the folding frames and supporting blocks.

RUBERT C. BOCKUS.
HENRY J. LANDRY.
